[57] CLAIM

The ornamental design for a hose nozzle, as shown and described.

DESCRIPTION

FIG. 1 is a perspective view taken from the top, rear and left side of a hose nozzle showing our new design; FIG. 2 is a top plan view thereof;

FIG. 3 is a left side elevational view thereof, the right side being a mirror image of the left side shown;

FIG. 4 is a front elevational view thereof;

FIG. 5 is a rear elevational view thereof; and

FIG. 6 is another left side elevational view thereof showing portions in cross section to illustrate recessed surfaces.

The broken line representation of a detachable spray unit in FIG. 1 is for purposes of illustration only and forms no part of the claimed design.

Fig. 1.
